UNITED STATES PATENT OFFICE.

ROBERT S. BLAKE, OF CHICAGO, ILLINOIS, ASSIGNOR TO BENJAMIN ELECTRIC MANUFACTURING COMPANY, A CORPORATION OF ILLINOIS.

TAPPING ATTACHMENT.

1,021,179.

Specification of Letters Patent. Patented Mar. 26, 1912

Application filed June 2, 1910. Serial No. 564,717.

To all whom it may concern:

Be it known that I, ROBERT S. BLAKE, a citizen of the United States, residing at Chicago, in the county of Cook and State of Illinois, have invented new and useful Improvements in Tapping Attachments, of which the following is a full, clear, concise, and exact description, reference being had to the accompanying drawing, forming a 10 part of this specification.

My invention relates to tapping attachments. By this I mean attachments for use in tapping electrical current from lead conductors and enabling it to be directed to 15 one or another of a variety of translating devices, and of which an electric lamp socket is a good example. Such attachments are often placed in readily accessible positions and usually have no protection against 20 thieves. Much annoyance and loss has been caused, for instance, by the loss of lamps from sockets which are located in accessible places. Since the advent of the tungsten and other more expensive forms of lamp 25 this has become a far more serious trouble than was before the case. Devices have from time to time been proposed for remedying this difficulty; for instance for preventing the unauthorized removal of lamps from 30 their sockets, but each of these devices has been subject to certain disadvantages.

It is the object, therefore, of my invention to provide a tapping attachment which is thief-proof and which is of such a nature 35 that it will be at once cheap of manufacture and convenient and efficient in use.

I have shown, by way of example, one embodiment of my invention in the accompanying drawings, but it is to be understood 40 that my invention may be embodied in other devices without exceeding the scope thereof as stated in the appended claims.

In the drawings:—Figure 1 is a longitudinal section taken through a plug lamp 45 socket constructed in accordance with my invention; Fig. 2 is a bottom plan view of the device; Fig. 3 is a horizontal section taken on the line 3—3 of Fig. 1 looking in the direction of the arrows; and Fig. 4 is a 50 detail view of a peculiar form of set screw which I may employ.

Referring now to the device which I have shown in the drawings as conveniently illustrating my invention, 10 is an insulating 55 base carrying upon the outside thereof a

contact sleeve 11 of a kind adapted for use in connection with a socket of the Edison type. The sleeve 11 is constricted at its lower portion to form a neck 12, the lower end of which is flared out to form a 60 flange 13.

14 is a lamp receiving shell having a flange 15 at its upper edge which engages over the flange 13 of the neck 12, the engagement being such as to permit a relative rotative movement between the shell 14 and the neck 12, while at the same time current is conveyed to the shell 14 from the sleeve 11 through the neck 12. The base 10 is provided with a central passage opening 70 into a wall or depression 16, which passage receives a conducting tube 17, the upper end of which is flanged over to form a central contact for making connection with the center contact of the socket. The tube 17 is retained in place by a ring 18 located in the depression 16 and secured to the tube in any desired manner. A stem 19 is slidably mounted in the tube 17 and is connected thereto by means of a spring 20 which is attached at one end to the tube 17 and at the other end to a head 21 upon a shank 19. It will be seen that the base 10, together with the sleeve 11 and tube 17 form a plug adapted to receive current from an ordinary Edison socket and that the rotatable shell 14 and center contact 21 form a lamp socket. 75

It will be seen that, the shell 14 being rotatable, a lamp cannot be inserted therein or removed therefrom unless the shell is held 80 against rotation, since otherwise the effect of turning the lamp would merely be to turn the shell 14 also, the lamp remaining stationary with relation to the threads of the shell. I provide means for normally 85 preventing access to said shell and thereby preventing removal of the lamp therefrom, such means being capable of being rendered inoperative when the plug portion of the device is not in place in a socket.

To the above end I provide a casing 22 which surrounds the shell 14 and the lower part of the base 10. Within this casing is placed an insulating ring 23, such ring being located in the annular recess formed by the neck 12 and being adapted to rotate upon said neck. The insulating ring 23 is provided with a screw threaded hole containing a set screw 24 which extends outward into a hole 25 formed in an insulating col- 100 105 110

lar 26 which is secured to the outside of the casing 22 at the upper edge thereof, the casing being provided with an enlarged slot 27 for admitting passage of the screw. The head of the set screw 24 normally lies about flush with the outer edge of the hole 25 and its end lies about flush with the inner surface of the insulating ring 23. When the parts are in this condition, the casing 22 can 10 rotate relatively to the rest of the device and it is consequently impossible to remove the plug from the socket, since access cannot be had to the plug to impart a rotating movement thereto. At the same time the 15 lamp cannot be removed from the rotatable shell 14 since that shell is protected by the casing, the open end of the latter being closed by the lamp.

The screw 24, may be turned until it 20 reaches the position shown in Figs. 1 and 3 of the drawings, in which position it engages in one of a plurality of holes 27 with which the neck 12 is provided. It will be seen that when the set screw is moved into 25 this position, the casing, ring 23, and sleeve 11 are locked together so that a rotating movement imparted to the casing 22 will effect a like rotating movement of the shell 11 and will permit the plug member to be 30 withdrawn. When the plug member has been withdrawn from the socket, the screw 24 may be taken out, whereupon the casing 22 can be rendered inoperative as a covering for the shell and by moving it forward relatively to the remainder of the device to expose the shell 14. The shell 14 may then be 35 grasped by hand and the lamp removed. In order to prevent manipulation of the set screw 24 by an unauthorized person, the 40 head thereof is provided with a specially shaped head 30 adapted to receive a special wrench. An insulating lining 28 is inserted in the shell 22 and is secured in place by rivets 29 which pass through the lining, 45 the casing, and the collar 26 thereby securing these parts in their relative position.

When the plug is in place in a socket and the screw 24 is moved back out of engagement with the neck 12, the plug cannot be 50 removed from the socket and the lamp cannot be removed from the shell. Even if a person should examine the device and find the head of the screw 24, he would have great difficulty in turning the screw without 55 the necessary special wrench. When, however, an authorized person desires to take out the lamp, he inserts the wrench into the end of the screw and drives the latter in until it reaches the position shown in Figs. 60 1 and 3 when the plug may be removed. He then removes the screw 24 which enables him to draw the casing 22 forward upon the plug to expose the shell 14, which latter may be grasped by hand to enable the lamp to 65 be withdrawn.

It will be seen that the device is simple and of a nature such that it can be manufactured upon an economical scale. Furthermore the device which I have chosen to show in the drawings has the great advantage that it may be used in connection with any existing form of socket. Those who find it necessary to provide against theft of lamps may do so by inserting this device into the sockets which they already have installed, no rewiring being necessary.

Having thus described my invention, what I claim as new and desire to secure by Letters Patent is—

1. In combination, a plug member, and a 80 casing member for said plug member rotatably mounted with respect thereto, one of said members being provided with means enabling said members to be locked together to permit the plug member to be rotated.

2. In combination, a plug, and an outer 85 casing for said plug rotatably mounted with respect thereto, said casing being provided with means enabling it to be locked to the plug to permit the latter to be rotated.

3. In combination, a plug, an outer casing 90 rotatably mounted upon said plug and covering the portion thereof which is exposed when said plug is inserted into a socket, and means for locking said casing to said plug to permit the latter to be rotated.

4. In combination, a plug, an outer casing 95 rotatably mounted upon said plug and covering the portion thereof which is exposed when said plug is inserted into a socket, and key-operated means for locking said casing to said plug to permit the latter to be rotated.

5. In combination, a base, a lamp terminal receiving contact mounted to rotate 105 with respect to said base, a second lamp contact, a casing surrounding said lamp terminal receiving contact and normally locked against movement to disclose the same, and means enabling said casing to be released so 110 that it may be moved to disclose said lamp terminal receiving contact.

6. In combination, a base, a lamp terminal receiving contact mounted to rotate with respect to said base, a second lamp contact, 115 means for normally preventing manual access to said lamp receiving contact, and means enabling said first-named means to be rendered inoperative when desired.

7. In combination, a base, a lamp terminal receiving contact mounted to rotate with respect to said base, a second lamp contact, means for normally preventing manual access to said lamp receiving contact, and key-operated means enabling said first-named 125 means to be rendered inoperative.

8. A plug lamp socket comprising a plug member, a lamp terminal receiving contact mounted to rotate with respect to said plug member, a second lamp contact, means for 130

normally preventing manual access to said lamp receiving contact, said means being capable of being rendered inoperative when said plug member is not in place in a socket, 5 and releasable means for preventing withdrawal of said plug member from a socket into which it has been inserted.

9. A plug lamp socket comprising a plug member, a lamp terminal receiving contact 10 mounted to rotate with respect to said plug member, a second lamp contact, a casing surrounding said lamp receiving contact and capable of being moved to disclose said contact when said plug member is not in place 15 in a socket, and releasable means for preventing withdrawal of said plug member from a socket into which it has been inserted.

10. A plug lamp socket comprising a plug member, a lamp receiving contact mounted

to rotate with respect to said plug member, a second lamp contact, a casing mounted to rotate with respect to said plug member and surrounding the portion of the device which is exposed when the plug member is in place 25 in a socket, said casing being adapted to be moved to disclose said lamp receiving member when said plug is not in place in a socket, and said casing being provided with means for enabling it to be locked to 30 said plug member to permit the latter to be rotated.

In witness whereof, I have hereunto subscribed my name in the presence of two witnesses.

ROBERT S. BLAKE.
